UNITED STATES PATENT OFFICE.

HENRY ALABASTER, OF SOUTH CROYDON, AND TOM ERNEST GATEHOUSE, OF CAMBERWELL, COUNTY OF SURREY, AND HARRY ROBERT KEMPE, OF BARNET, COUNTY OF MIDDLESEX, ENGLAND.

TELEPHONE.

SPECIFICATION forming part of Letters Patent No. 314,304, dated March 24, 1885.

Application filed September 20, 1884. (No model.) Patented in England June 7, 1882, No. 2,675; in France December 7, 1882, No. 152,487, and in Germany December 9, 1882, No. 23,992.

To all whom it may concern:

Be it known that we, HENRY ALABASTER, of South Croydon, in the county of Surrey, and TOM ERNEST GATEHOUSE, of Camberwell, 5 in the same county, and HARRY ROBERT KEMPE, of Barnet, in the county of Middlesex, in England, all citizens of Great Britain, have invented certain new and useful Improvements in Telephones, (patented also in 10 Great Britain June 7, 1882, No. 2,675; in France December 7, 1882, No. 152,487, and in Germany December 9, 1882, No. 23,992,) of which the following is a specification.

Our invention relates to a novel construction and arrangement of a telephonic receiving-instrument, and to the combination therewith of any known transmitting-instrument.

The object of our invention is to produce increased efficiency in telephonic apparatus, 20 and this we effect by the use of the apparatus which we now proceed to describe.

At each end of a suitable case we fix a plate and stretch between these plates an iron or steel wire, round which are closely wound two 25 coils of insulated wire. One of these coils, which may be of coarse wire, connects the poles of a local battery. The other coil, which is preferably of fine wire, is connected to the line at its one end and to earth at its other end.

When electrical undulations produced by 30 pulses of sound on a transmitting-instrument of any known kind are sent along the line, the iron or steel wire of the receiving-instrument above described is acted on electro-magnetically, and its plates are caused to vibrate by conduction of the magnetic vibrations from the wire to the plates, reproducing the sounds which actuate the transmitter. It is convenient to inclose the two plates of the instrument 35 in casings, and lead from these casings flexible tubes, so that the sounds can be conveyed to both ears. A transmitting-instrument of any known kind can be connected into the wire of the local battery, and this 40 transmitter will serve for sending to the distant station.

Figure 1 of the accompanying drawings

represents a telephonic receiving-instrument according to our invention, with its connections shown diagrammatically.

The instrument, as shown in Fig. 1, consists of a thin wire, A, of iron, steel, or other magnetic metal, attached to two disks, D D, which may be of thin wood, or of metal, or of other more or less sonorous material. On the 50 wire A is wound, in the first place, an insulated conducting-wire, W, completing the circuit of a local-battery B, in which circuit may be introduced any known telephonic transmitting-instrument T; also, on the wire A 55 is wound, in the second place, an insulated wire, X, forming part of the line-circuit L L', communicating with a distant station. When electrical impulses are set up in the line L L' at the distant station by a telephonic transmitter, sounds corresponding with those that caused the impulses are emitted by the instrument shown in Fig. 1.

The instrument may be connected as shown diagrammatically by Fig. 2.

The disks D D may form the ends of sound-boxes S S, having flexible tubes leading from them to funnel-mouths E E, that can be held to both ears; also, the one wire W may include in its circuit the primary coil of an inductorium, I, the other wire, X, including in 75 its circuit the secondary coil of the inductorium.

Having thus described the nature of our invention and in what manner the same is to be performed, we would have it understood that we make no general claim to the use of an iron or steel wire coiled with a conducting-wire for producing sounds under the influence of electric currents; but

We claim—

1. In a telephonic receiver, the combination consisting of two resonating disks, a wire or rod of magnetic material stretched between them perpendicularly to their faces, and a coil 80 of insulated wire in an electric circuit surrounding the magnetic wire or rod.

2. In a telephone, the combination of two resonating boxes, with a magnetic rod extend-

ing between and secured to the same, an inductorium having its primary in a local-battery transmitter-circuit, which also includes a coil upon the magnetic rod, and its secondary in the line-circuit, which includes another coil upon said rod, and flexible listening-tubes proceeding from the resonator - boxes, substantially as described.

Signed at 6 St. Dunstans Hill, London, in

the county of Middlesex, in England, this 6th 10
day of August, 1884.

HENRY ALABASTER.
TOM ERNEST GATEHOUSE.
HARRY ROBERT KEMPE.
